NAIL STRIPPER

Howard L. Snyder, Sodus, N. Y.

Application November 16, 1945, Serial No. 629,147

6 Claims. (Cl. 1—49.7)

1

My invention relates to improvements in the type of nail stripper in which the nails automatically align themselves so that they may be withdrawn with their heads up.

The primary object of my invention is to provide a nail stripper of the character indicated which can be readily adjusted to feed the nails gravitationally at different rates and for the purpose of accommodating nails of different sizes.

Another important object of the invention is to provide a nail stripper of the above indicated character which can be readily knocked down and set up, and which when knocked down can be readily assembled into a convenient, compact box-like form, enabling the device to be carried by the workman to and from the work.

Another important object of the invention is to provide a device of the character indicated above which can be easily and inexpensively manufactured from sheet metal and wire, in a sturdy and practical form, making possible its merchandizing at an attractively low price.

Other important objects and advantages of my invention will be apparent from a reading of the following description and the accompanying drawings, wherein a merely illustrative example of the invention is shown.

In the drawings:

Figure 1 is a vertical longitudinal sectional view taken along the line 1—1 of the device of Figure 3 set up in operative position.

Figure 2 is a perspective view of the device on a reduced scale showing it knocked down and assembled in carrying condition.

Figure 3 is a transverse section taken through Figure 1 along the line 3—3 and looking in the direction of the arrows.

Figure 4 is a fragmentary elevational view of the depressed end of the lower slide rod assembly.

Figure 5 is similar view of the elevated end of the lower slide rod assembly.

Figure 6 is a fragmentary perspective view on an enlarged scale taken from the right hand side of Figure 4.

Figure 7 is a transverse section taken along the line 7—7 of Figure 1.

Referring in detail to the drawings, my improved nail stripper comprises the base 7 which is an elongated rectangular box form having the low end wall 8 and the higher end wall 9 with side walls 10 of conformably tapering height. By means of the hinge 11 attached to the outside of the upper part of the base wall 9 the up-

2

right support 12 is connected to and supported from the base 7.

The upright support 12 is a parallel sided box form similar to the base and complementary thereto so that when the support 12 is hinged downwardly it mates with the base 7 to form the flat box shape illustrated in Figure 2 and encloses all of the remaining component parts of the device in compact carrying condition. A hook 13 on the high end of the support 12 may then be engaged with a keeper 14 on the low wall of the base to lock the device in carrying condition. The sheet metal upright portion 15 of the support 12 may be thickened or reinforced for a part of its length to provide an adequately rigid area 16 formed with longitudinally spaced holes 17 for a purpose hereinafter described.

The upper slide 18, in which the nails 19 to be stripped are placed is a rectangular elongated three sided box form having the open depressed end 20 and downwardly converging sidewalls. The elevated end has laterally spaced hooks 21 fixed on the lower part of its endwall 22 which supportably engage through holes provided for their reception in the upper part of the upright portion 15 of the vertical support 12 to thereby form a pivotal supporting connection between the elevated end of the upper slide and the upper part of said upright. Bolts 23 having one end pivoted through holes in the sidewalls of the upper slide 18 near the elevated end above the stationary hooks 21, have their threaded parts passed through holes provided for the purpose in the upright portion 15 of the support 12, and wing nuts 25 are threaded thereon against the outside of said bottom. One of the bolts 23 is sufficiently shorter than the other to enable them to be engaged in their holes one at a time, the wing nut 25 being threaded on the longer before the shorter bolt is engaged in its hole, whereat both wing nuts 25 are threaded further on the bolts to raise the slide 18 to the desired angle of inclination suited to causing the nails 19 placed thereon to slide toward the depressed end as indicated in Figure 1. The bolts 23 may be unevenly tightened to give lateral tilt to the slide 18 where conditions require. Diagonal wire or rod braces 26 have inturned ends removably inserted in the side walls of the base and upright to hold them substantially at right angles.

The lower slide 27 which receives the nails falling off the depressed end of the upper slide is shorter in length and narrower than the widest part of the upper slide and generally rectangular in outline. Hooks 27a on the upper part of its

sides loosely engage eyes 28a depending from the depressed end of the upper slide 18 to suspend the lower slide from the upper slide. The lower slide 27 is composed of two inner hollow isosceles triangular forms 28 and 29 (see Figure 3) and two outer right triangular hollow forms, 30 and 31, the adjacent forms being assembled together by a plate 32' to which their elevated ends are fixed and whereby the elevated ends of the forms 29 and 31 and 28 and 30 have a fixed maximum lateral spacing. The upper ends of ends of the two inner hollow triangular forms, 28 and 29, and the two outer triangular hollow forms, 30 and 31, Figures 1 and 7, are secured to the inner face of the end wall of the slide 27 as by welding or the like. Their adjacent lower edges 32 and 33 and 34 and 35, respectively, act as nail tracks at the bottom of the nail troughs formed by the adjacent triangular forms. The nail tracks are arranged so that they are narrower than the heads of the nails, so that when the nails fall from the upper slide 18 into the trough their shanks fall through the tracks and the nails become slidably suspended by their heads in the tracks.

The lower ends of the triangular forms are adjustable transversely to vary the width of the nail tracks or nail slots by means of an arrangement which includes a threaded rod 35 which passes through upright single flanges 36 on the outer triangular forms and upright double flanges 37 on the inner triangular forms. Pairs of wing nuts 38 threaded on the rod 35 on opposite sides of the various upright flanges enable adjusting the adjacent triangular forms toward or away from each other to correspondingly vary the width of the nail slots or tracks to accommodate nails of different sizes.

As the nails 19 slide gravitationally off the depressed ends of the nail tracks they fall in upright position into nail slides which are aligned with and below the nail tracks on the lower slide 27, and from which they may be readily removed in such upright or erect position by the workman by removing them one or more at a time from the elevated end of any nail slide as needed.

Each nail slide consists of a pair of parallel rods or heavy wires 39 and 40 which have their elevated ends bent upwardly and laterally outwardly in opposite directions as clearly shown in Figure 3. The upper end of each of the rods 39 and 40 are connected to the bottom of the triangular hollow forms 28, 29, 30 and 31 complementary thereto, as indicated by the numeral 42. The lower end of each of the rods 39 is connected to the transverse rod 43, and the lower end of each of the rods 40 is looped at 45 about a threaded rod 46. The rod 43 has its opposite ends bent inwardly, as indicated by the numeral 47. Arranged above the rod 43 and suitably spaced therefrom is another transverse rod 44 which likewise has its opposite ends bent inwardly, as indicated by the numeral 47. The complementary bent ends 47 of the rods 43 and 44 are connected as by welding or the like to supporting or brace rods 49.

The other ends of the supporting or brace rods 49 are fastened as by welding to the sides of the lower slide 27.

Threaded on the rod 46 on each side of the loop 45 of each adjustable rod 40 is a pair of wing nuts 50 by means of which the nail slide rod 40 may be adjusted toward or away from its companion fixed nail slide rod 39 to accommodate

different sizes of nails, and fixed securely in any adjusted position.

Also looped around the threaded rod 46 at 51 between the wing nuts 50 of the middle or other suitable nail slide is the depressed end of the swingably detachable brace rod 52. The elevated end of the brace rod 52 is bent and threaded as indicated at 53 to pass through any selected one of the holes 17 in the upright support 12 and receive thereon a wing nut 54, whereby the lower slide and nail slides are securely held at a declining angle determined by the particular one of the holes 17 in which the adjustable brace rod has been inserted.

When it is desired to knock down the device to the portable box form shown in Figure 2 of the drawings, the wing nut 54 is backed off and the threaded end of the rod 52 removed from the hole 17 and the rod tilted toward the right in Figure 1. The hooks 21a of the lower slide are then disengaged from the eyes 28a on the upper slide and the lower slide then deposited as a whole in the base 7.

The wing nuts 25 are then backed off the pivoted bolts 23 and the hooks 21 disengaged from their holes in the support 12 and the upper slide is then inverted and placed in the base 7 over the lower slide.

The diagonal braces 26 are then disconnected from the side walls of the upright support 12 and base 7 and placed inside the base, and the support 12 is then swung down upon the base into the position shown in Figure 2 and locked in place by means of the hooks 13. To set up the device substantially the reverse of the above described operation is performed.

What I claim is:

1. A nail stripper comprising a base, an upright supported on said base, an upper slide for holding nails, a pivotal supporting connection between the elevated end of the upper slide and the upper part of said upright, elements connected to and between the upright and the upper slide at points above the pivotal connection, said elements being adjustable to determine and fix the declining angle of the upper slide, a lower slide positioned beneath the depressed end of the upper slide to receive nails therefrom, means tiltably suspending the lower slide from the depressed end of the upper slide, said lower slide having longitudinal troughs including nail slots and being tilted at an opposite angle from the upper slide, a framework secured to the lower slide and positioned thereunder and extending beyond the depressed end of the lower slide toward and terminating in spaced relation to the said upright, said framework comprising nail slides longitudinally aligned with said nail slots, a detachable brace rod pivoted at its lower end to the depressed end of said framework and having a terminal portion at its upper end selectively insertible in any one of a plurality of vertically spaced openings formed in said upright so as to determine the declining angularity of said lower slide and framework, and means for securing said terminal portion in the opening selected.

2. In a nail stripper of the type comprising a base, an upright supported thereon, an upper declining slide to receive in bulk nails to be stripped, a declining lower slide beneath the depressed end of the upper slide to receive nails falling from the depressed end of the upper slide, said lower slide having a framework arranged to extend beyond and at a level below its depressed end, said framework comprising pairs

of substantially parallel longitudinal rods having depressed ends spaced to provide nail slides, a cross rod supportably connected to the lower slide and to which the depressed end of one rod of each pair is fixed, a threaded cross rod supported on said framework parallel to said cross rod, with the depressed ends of the remaining rods of said pairs having loops circumscribed thereon, and nuts threaded on said threaded rod on opposite sides of the loops to enable adjusting and fixing the spacing of the said remaining rods relative to the fixed rods so as to accommodate the nail slides to nails of different sizes.

3. In a nail stripper of the type comprising a base, an upright supported thereon, an upper declining slide to receive in bulk nails to be stripped, a declining lower slide beneath the depressed end of the upper slide to receive nails falling from the depressed end of the upper slide, said lower slide having a framework and arranged to extend beyond and at a level below its depressed end, said framework comprising pairs of substantially parallel longitudinal rods having depressed ends spaced to provide nail slides, a cross rod supportably connected to the lower slide and to which the depressed end of one rod of each pair is fixed, a threaded cross rod supported on said framework parallel to said cross rod, with the depressed ends of the remaining rods of said pairs having loops circumscribed thereon, nuts threaded on said threaded rod on opposite sides of the loops to enable adjusting and fixing the spacing of the said remaining rods relative to the fixed rods so as to accommodate the nail slides to nails of different sizes, means tiltably suspending the lower slide from the upper slide, and an adjusting brace pivoted at its lower end to said framework cross rod and selectively connectible at its upper end to any of a number of vertically spaced points on said upright so as to determine the angle of declination of said lower slide and said nail slides.

4. In a nail stripper of the type comprising a base, an upright supported thereon, an upper declining slide to receive in bulk nails to be stripped, a declining lower slide beneath the depressed end of the upper slide to receive nails falling from the depressed end of the upper slide, said lower slide having declining troughs defined by pairs of longitudinally extending downwardly converging plates spaced at their lower ends to define nail slots of a width permitting the shanks of nails to fall through while the heads are retained to support the nails in erect position, means connecting the plates at the elevated end of the lower slide and fixedly maintaining their spacing at the elevated end of the lower slide, adjusting means on the depressed end of the lower slide and engaging the pairs of converging plates for adjusting and fixing the spacing of the lower edges thereof relative to each other so as to change the width of the nail slots to accommodate nails of different sizes, said adjusting means comprising a threaded rod passing transversely through portions of the depressed ends of said plates, and nuts threaded on said threaded

rod on opposite sides of each plate whereby the paired plates can be laterally adjusted toward or away from each other by turning the nuts on the threaded rod.

5. In a nail stripper of the type comprising a base, an upright supported thereon, an upper declining slide to receive in bulk nails to be stripped, a declining lower slide beneath the depressed end of the upper slide to receive nails falling from the depressed end of the upper slide, said lower slide having hollow forms of triangular cross section paired to provide downwardly converging walls forming troughs with their lower edges spaced to define nail slots, means connected to and fixing the spacing of the elevated ends of said triangular forms, flanges on the depressed ends of said triangular hollow forms, a transverse threaded rod passing through the flanges, and nuts threaded on the rod on opposite sides of the flange of each form whereby the triangular forms may be adjusted laterally to vary the width of the nail slots to accommodate nails of different sizes.
6. In a nail stripper of the type comprising a base, an upright supported thereon, an upper declining slide to receive in bulk nails to be stripped, a declining lower slide beneath the depressed end of the upper slide to receive nails falling from the depressed end of the upper slide, said lower slide having hollow forms of triangular cross section paired to provide downwardly converging walls forming troughs with their lower edges spaced to define nail slots, means connected to and fixing the spacing of the elevated ends of said triangular forms, flanges on the depressed ends of said triangular forms, a transverse threaded rod passing through the flanges, nuts threaded on the rod on opposite sides of the flange of each form whereby the triangular forms may be adjusted laterally to vary the width of the nail slots to accommodate nails of different sizes.
